UNITED STATES PATENT OFFICE

2,420,054

NECKTIE

Max M. Newman and Victor M. Newman,
New York, N. Y.

Application January 19, 1944, Serial No. 518,809

3 Claims. (Cl. 2—146)

1

Our invention relates to a new and improved four-in-hand necktie. The principal object thereof is to provide a self-draping necktie which when knotted will form a proper longitudinal fold below the knot portion of the tie.

Other objects of the invention are to provide an improved necktie construction which will—

(1) Assist in the proper formation and alignment of the dimple below the knot portion of the tie;

(2) Render the necktie more pliable;

(3) Preserve the shape of the tie either when knotted or in flat condition;

(4) Assist in the proper formation of the knot; and

(5) Prolong the life of the tie.

We accomplish all of the foregoing, in accordance with our invention, by connecting the lining to the rear body of the necktie by means of intersecting zigzag or diagonal lines of wire stitching, as will be hereinafter more fully described. As another embodiment, only the lining of the necktie is provided with the intersecting zigzag lines of wire stitching.

Numerous additional objects of our invention are stated in the annexed description and drawings, which illustrate preferred embodiments thereof.

Fig. 1 is a rear elevation of the first embodiment.

Fig. 2 is a sectional view on the line 2—2 of Fig. 1.

Fig. 3 is a front elevation of the second embodiment, in complete made-up form, shown partially broken away to illustrate the lining construction.

Fig. 4 is a sectional view on the line 4—4 of Fig. 3.

Fig. 5 is a view similar to Fig. 4, but showing two dimples below the knot portion instead of one as in Fig. 4.

Fig. 6 is a sectional view on the line 6—6 of Fig. 3.

Fig. 7 is an enlarged plan view of a portion of the rear of the necktie illustrated in Fig. 1.

Referring to Figs. 1, 2 and 7 of the drawings, the necktie comprises the usual front wide end 1, the rear narrow end 2, and the usual lining 11. Reference numeral 10 designates the material of the necktie.

Lining 11 is stitched to the rear face of the front wide end 1 of the necktie by means of the diagonal or zigzag lines of wire stitching 12 which pass through said lining and through the rear face of said wide end of the necktie. These

2

lines of wire stitching intersect each other at a number of points to form a plurality or series of similarly shaped vertically aligned parallelogram sections, as shown in Figs. 1 and 7. It will be noted that said lines of wire stitching 12 are located in the knot area or portion of the necktie and extend from the lower part of the wide end 1 of the necktie to the beginning of the neck portion of the necktie.

10 Hence the wire stitches extend to and they may be located in, the knot-forming portion of the necktie.

By using a relatively thin and fine wire as the connecting means, the necktie is rendered more

15 pliable and, most important of all, when the necktie is knotted the tie is self-draping. That is, the necktie when knotted has a tendency to form a longitudinal pleat or fold below the knot portion. This pleat or fold is formed substantially at the common vertical axes of the sections formed by the intersecting lines of wire stitching 12.

20 There are also provided supplemental lines of thread stitches 13 which pass through lining 11 and through the rear face of the front wide end 1 of the necktie and around the wire stitches 12.

25 Stitches 13 are parallel to wire stitches 12. It is not absolutely essential to provide the lines of thread stitching in order to accomplish the ob-

30 jects of our invention and the same may be omitted if desired.

35 When the necktie is in the complete made-up form illustrated in Fig. 3, the wire stitching 12 or the thread stitching 13 is not discernible as the rear face of the front wide end 1 of the necktie is not visible when the tie is worn.

In the embodiment illustrated in Figs. 3 to 6, only the lining 23 of the necktie is stitched with the wire 24. The wire stitches do not pass 40 through any part of the necktie and are solely confined to the lining.

45 The necktie illustrated in this embodiment comprises the front wide end portion 21, the rear narrow end portion 22, and the lining 23. Reference numeral 20 indicates the material of the necktie.

As shown in Figure 3, lining 23 is provided with zigzag lines of wire stitching 24 which intersect each other at a number of points to form 50 a plurality of vertically aligned parallelogram-shaped sections. The wire stitches 23 extend from the lower part of the front wide end of lining 23 substantially to the neck portion thereof. The wire stitching 23 is not supplemented by any thread stitches.

Fig. 4 shows the formation of a single dimple below the knot portion of the necktie. Fig. 5 shows the formation of a double dimple.

By forming a plurality of vertically aligned parallelogram sections with intersecting zigzag lines of wire stitching, the necktie when knotted has a tendency to form a longitudinal pleat or fold below the knot portion along the vertical axis of each parallelogram section. As the vertical axis of each parallelogram section is in alignment, said longitudinal pleat or fold will persevere be continuous. The wire stitches or members extend transversely oppositely from the longitudinal axis of the necktie and its lining. The use of wire stitching renders the necktie very pliable and assists in the proper formation of said longitudinal pleat or fold. The wire which is used for making the stitches is bendable and it is sufficiently rigid to hold the dimple shape which is shown in Figs. 4 and 5.

In the first embodiment, that is where the wire stitching passes both through the lining and the rear face of the wide end of the necktie, the stitches 12 and 13 will not be discernible when the necktie is completely made up. Even if such stitches are visible, the wire and thread which is used for making such stitches can be of the same color as the material of the necktie, or if desired, a thread covered wire may be used. The dimple effect is secured by transversely bending the non-resilient and transversely disposed wire stitching, which is located in or directly adjacent the knot-forming portion of the necktie.

We claim:

1. A four-in-hand necktie which has transversely-disposed bendable and non-resilient wire members connected thereto and located adjacent the knot-forming portion of said necktie, said wire members being transversely bendable and retaining their transversely bent shape to produce at least one transverse dimple adjacent the knot of said necktie when said necktie is knotted, said wire members extending transversely oppositely from the longitudinal axis of said necktie, said wire members being located in the outer

member of the necktie and forming a longitudinal series of successive parallelograms.

2. A four-in-hand necktie which has transversely-disposed bendable and non-resilient wire members connected thereto and located adjacent the knot-forming portion of said necktie, said wire members being transversely bendable and retaining their transversely bent shape to produce at least one transverse dimple adjacent the knot of said necktie when said necktie is knotted, said wire members extending transversely oppositely from the longitudinal axis of said necktie and being located in the outer member of the necktie, said necktie having a lining, said necktie also having transverse folds at its inner face, said wire members connecting said lining to the transverse folds at the outer end of said necktie.

3. A lining for a four-in-hand necktie, said lining having transversely-disposed and non-resilient wire members connected thereto and located adjacent the knot-forming portion of said necktie, said wire members being transversely bendable and retaining their transversely bent shape, said wire members extending transversely oppositely from the longitudinal axis of said necktie and forming a longitudinal series of successive parallelograms.
